UNITED STATES PATENT OFFICE.

EDWARD A. TUTTLE, OF NEW YORK, N. Y.

EXERCISING-MACHINE.

SPECIFICATION forming part of Letters Patent No. 281,869, dated August 31, 1880.

Application filed September 25, 1879.

To all whom it may concern:

Be it known that I, EDWARD A. TUTTLE, a resident of the city of New York, in the county and State of New York, have invented 5 a new and useful Improvement in Exercising-Machines, (Case B,) of which the following is a specification.

This invention consists of a guideway and roller so combined and arranged relatively to 10 the platform that its level is maintained when rising and falling without the parallel bar or lever contrivance commonly used for that purpose, and with only one pivot connection of the levers to it.

15 The construction is simpler, the action better, and the wear less than in the aforesaid parallel-bar contrivance.

Figure 1 is partly a side elevation and partly 20 a section of my improvement. Fig. 2 is a plan of the under side of the machine.

A represents the platform, on which the operator stands to raise and lower himself by the levers B, which he works by the handles C. These levers have their fulcrums on the standards D of the base E, and are pivoted to the 25 platform at F for locking it, said pivots being located between the place where the operator stands—say at G—and the opposite end of the platform.

30 Near the center of the base E, I have lo-

cated a curved guideway, H, which is so situated that the roller I, mounted on the underside of the platform A by a bracket, J, will run on the same, thereby maintaining the level of the platform while rising and falling. The radius 35 of the curve of this guideway is the same as the distance between pivots F and fulcrums D, less half the diameter of the roller. The arrangement is such that the platform is a little heavier on the side of pivots F upon which 40 the operator stands than on the other side, so that the roller keeps its level by bearing against the guide. The bracket might bear upon the guide without the roller, but it would make needless friction. There may be two 45 such guides and rollers, if preferred, one near each side of the platform; but it is believed that one in the middle is just as good.

Having thus fully described my invention, what I claim, and desire to secure by Letters 50 Patent, is—

The combination of one or more guideways, H, and a roller, I, with the movable platform and levers of an exercising-machine, to maintain the level condition of the platform, substantially as described. 55

EDWARD A. TUTTLE.
